UNITED STATES PATENT OFFICE.

LOUIS B. CAMPBELL, OF WAKARUSA, KANSAS.

PATRON'S SERVICE ENVELOPE.

Application filed July 2, 1925. Serial No. 41,137.

My invention relates to patron's service envelope. The object of my invention is to provide an envelope for persons living in the rural districts in which to place their mail and place same in the mail box for transportation to the post office by the mail carrier, and there to be opened and the contents removed, obviating the loss of any of the articles sought to be mailed.

A further object of my invention is to provide an envelope having the patron's name thereon so that the mail can also be placed therein and delivered to its owner.

A still further object of my invention is to provide an envelope having a pocket attached thereto in which to place stamps or money and a note with instructions as to the purpose for which it is to be applied and also the pocket to receive a card with a portion of one side visible having information printed thereon and the card being square, eight instructions may be printed thereon and any one placed in view when the flap of the envelope is opened.

A still further object of my invention is to provide an envelope having a slot to receive the point of the flap and the slot to be closed by the side folds, protecting the contents from exposure therethrough.

These and other objects will hereinafter be more fully explained.

Referring to the drawings.

Fig. 1 is a view showing the envelope closed, parts broken away for convenience of illustration.

Fig. 2 is a view showing the flap opened but the printed instructions omitted.

Fig. 3 is an end view with the folds partly opened.

Fig. 4 is a view of the envelope completely unfolded with one of the folds broken for lack of space for its full extent.

Fig. 5 is a view of one side of the information card.

Fig. 6 is the opposite side view of the card.

In the drawings 1 is the flap and when being opened or closed it will bend on the dotted line A which is spaced above the edge B of one of the folds, providing space for the protruding end of the instruction card hereinafter described.

In Fig. 4 I have shown approximately the shape of the envelope before being

folded. I have shown thereon representations of mail matter such as letters C, and C'. To fold the envelope which is provided with folds 2 and 3, the said folds are bent on dotted lines D, and D'. When folded their positions are as shown by dotted lines E, and E', the endslapping each other as at F. When this is folded a second fold is made as shown by dotted line G. Then the flap 1 being closed with its point H entering the slot 4 the envelope then appears as shown in Fig. 1.

When the letters or other contents are inclosed note the fold 3 laps over slot 4 as shown in Fig. 4, and when the fold on line G is made the slot is closed from the contents by said fold 3 which is protected from direct contact by rain, snow or other damaging elements.

The pocket 5 is attached to or may be made integral with the envelope, that is to say being a part of the sheet so cut that by folding the ends and side it will form a pocket without being attached by mechanical means.

The said pocket is adapted to hold an instruction card 6 with one edge exposed, having printed instructions thereon and the said card being square will have different instructions parallelling, and in close proximity to each of the four edges and on both sides thereof, being a total of eight instructions and what ever instruction is desired the attention will be brought to bear by the instruction on the edge protruding from the pocket.

The bending line A as shown in Fig. 1 is spaced from the edge of the last fold as at B so that the instruction card 6 will not be broken when the flap 1 is closed.

The said pocket is also adapted to hold money, stamps or notations with detailed instructions on matter of business between the patron and the post office, and likewise any business or information to be extended to the patron from the post office.

On Fig. 1 is shown certain printed matter of instructions, and that shown on the flap 1 is for the change of address of the patron, and also the title of the envelope.

On the envelope below the flap is a brief instruction as to its uses by the patron and likewise for the mail carrier.

In the construction of my service envelope I do not confine myself to any particular

kind of material, and the size and shape may be varied as lies within the scope of the appended claim.

Having thus described my invention,
what I claim as new and desire to secure by
Letters Patent is:—

In a patron's service envelope, a nonsealable envelope, a pocket attached to the outside of the envelope and concealed by the
flap being placed between the top edge of
the envelope and the slot, said pocket being

sealed on three sides and having one side open, an instruction card placed within said pocket so that one edge thereof is exposed, printed instructions along the edges of said 15 card, said instructions being visible above the edges of the pocket, a fold in the flap positioned to break at the exposed edge of the card for convenience of closing the flap without forcing the card downward, all as 20 and for the purpose described.

LOUIS B. CAMPBELL.
